UNITED STATES PATENT OFFICE.

WILLIAM B. FENN, OF WINFIELD, NEW YORK, ASSIGNOR TO EZRA D. BECKWITH, OF SAME PLACE.

DESIGN FOR A WATER-BOTTLE.

SPECIFICATION forming part of Design No. 32,428, dated April 3, 1900.

Application filed March 7, 1900. Serial No. 7,729. Term of patent 3¹ years.

To all whom it may concern:

Be it known that I, WILLIAM B. FENN, a citizen of the United States, residing at West Winfield, in the county of Herkimer and State 5 of New York, have invented and produced a new and original Design for Water-Bottles; and I do hereby declare the following to be a full, clear, and exact description of the same, reference being had to the accompanying 10 drawing, forming part thereof, and in which the figure is a side elevation of a water-bottle embodying my design.

A represents the body or base of the bottle and which is substantially elliptical or oval 15 in contour.

B represents the neck, which extends vertically from the upper portion of the base of the bottle, said neck having a lower flaring surface B'.

20 C represents a ring which has a continual curved surface extending from the said flaring surface of the neck to the upper surface

of the elliptical or oval-shaped base, forming an inwardly-extending portion C', which joins the flaring surface of the neck, and a downwardly-directed portion C², which joins the upper portion of the base. 25

The essential features of my design consist in, first, the elliptical or oval base, the vertical neck extending from the upper central portion of the base, said neck having a lower outwardly-flaring portion, a ring having an upper inwardly-directed portion which joins the said flaring portion, and a lower downwardly-directed portion which joins the upper portion of the base. 30

I claim as my invention—

The design for a bottle, substantially as herein shown and described.

WILLIAM B. FENN.
